METHOD AND APPARATUS FOR PACKAGING BEVERAGES

Samuel Henry Ayers, Baltimore, Md., assignor to Crown Cork & Seal Company, Inc., Baltimore, Md., a corporation of New York

Original application October 25, 1938, Serial No. 236,948. Divided and this application May 11, 1943, Serial No. 486,570

4 Claims. (Cl. 226—70)

The present invention relates to methods and apparatus for packaging beverages and, more particularly, to the removal of air from receptacles containing beverages.

The present application is a division of my application for Methods and apparatus for packaging beverages, Serial No. 236,948, filed October 25, 1938.

The principal object of the invention is to provide a method and apparatus for removing air from the headspace of a receptacle containing a carbonated beverage such as beer or a soft drink.

In filling containers with carbonated beverages, and particularly beer, it is highly desirable to exclude air from the headspace of the container, since it is found that the oxygen of such air causes, or at least accelerates, changes in the flavor and turbidity of the beer.

Various means have been used to expel the air from the container headspace, but all such methods heretofore proposed have involved certain variable factors. For example, one previous method has involved tapping each bottle during its movement on the filling machine from the filling mechanism to the crowning mechanism, the tapping means being arranged to strike each bottle and thereby agitate the contents so that carbon dioxide would be liberated to expel the air from the headspace just prior to crowning. The difficulty with this method has been that since the walls of the main or body portions of bottles of the same rated capacity may vary rather widely in thickness, the tapping mechanism had to be adjusted to strike the thickest possible container sufficiently sharply to agitate the contents to the necessary extent. As a result, a bottle having a relatively thin wall would receive too sharp a blow, with the possibility that the beer therein would be agitated to such an extent that uncontrolled foaming would occur, with resultant waste.

By the method and apparatus of the present invention, heat is applied to the container to liberate carbon dioxide from the beverage to force the air from the container headspace, so that when the container is subsequently sealed, substantially no air will be confined in the container with the beverage.

The method and apparatus of my invention, involving the application of heat to the container, avoids all variable factors encountered in the use of prior apparatus and methods. For example, the temperature of a beverage, when flowed into a container, can be readily controlled, and the

gas content of any batch can also be readily ascertained. Thus if the temperature of the heat employed in my invention is controlled, and also the length of application of heat, no variable factors will be involved and substantially all air will be positively forced from the headspace of the container.

By my invention, bubbles will rise from the liquid to form a foam which is stable, as distinguished from ordinary uncontrollable foaming similar to boiling. The foam formed by the present invention, particularly on beer, will remain in place for several minutes and, in every instance, will remain in place until the container can be sealed.

Thus, by the use of the method and apparatus of the present invention, only sufficient inert gas will be liberated from the beverage to substantially remove all air from the container headspace and I obviate all possibility of undesirable foaming; that is, such foaming as will continue indefinitely.

A particular object of the present invention is to provide a method and apparatus for producing foam in a beverage without moving any tube or fluid into the beverage.

Some bottlers object to methods of producing foam which involve the introduction of a nozzle or the like into the beverage, it being their position that these nozzles may become contaminated during their exposure to the surrounding air. Some bottlers also object to the jetting of even inert gases or steam into beverages on the ground that these may change the flavor of the beverage. The present invention overcomes all such objections because it does not involve the movement of a nozzle into the beverage or the jetting of any substance into the beverage.

Another object of the invention is to provide an apparatus for forming foam on a beverage which does not require the provision of any parts which must be synchronized with the movement of filling heads.

Other objects and advantages of the invention will be apparent from the attached drawing, wherein:

Figure 1 is a horizontal sectional view taken above the work table of a filling machine of well-known construction and showing a modified arrangement for heating containers;

Figure 2 is a vertical sectional view on the line 2—2 of Figure 1, and

Figure 3 is a view in vertical section showing a mechanism for partially immersing containers in suitably heated water.

Referring to Figures 1 and 2, the reference numeral 10a designates the work table of a filling machine including a rotary filling table 11. Containers, preferably cans, are removed from the filling table by a dial 40 which transfers them to the crowning mechanism 12. A tunnel 41 of generally inverted U-shaped form in vertical section overlies the portion of the transfer dial 40 about which containers move, and the can C will move through this tunnel when traveling from the filling table to the crowning mechanism. As best shown in Figure 2, the tunnel 41 encloses the upper portion of the can and is provided with baffle plates 42 between which the neck of the container passes, the baffles 42 thereby defining, with the top and upper side walls of the tunnel, a chamber 43 through which the upper portions of the bottles pass. Electrical heating units 44 are provided on the inner surfaces of the side walls of the tunnel so that the air within the tunnel is maintained in a heated state. If desired, closed steam coils may be used as the heating means for the chamber 43. Thermostatic means may be provided in the chamber 43 to control its temperature.

By the arrangement shown in Figures 1 and 2, the upper portions of the containers will pass through a body of highly heated air so that the upper portions of the containers as well as the upper portion of the contents of the container will be heated to a sufficient degree to cause carbon dioxide to rise, usually in the form of compact controllable foam, from the upper part of the liquid within the containers.

It is to be noted that the tunnel 41 is kept in a heated state by heating the air therein. The use of heated air is found to be highly desirable since it does not cause such an increase in pressure within the chamber as would prevent carbon dioxide from freely rising from the beverage. For example, if free steam were used within the tunnel, the atmosphere within the tunnel would be under some pressure and, as a result, the carbon dioxide could not readily rise from the beverage.

It will be noted that the structure of Figures 1 and 2 can be applied to any usual type of filling machine, since the tunnel only covers a portion of the infeed dial.

In some instances, the application of localized heat to other areas than the top portion of the container is found satisfactory; for example, where the beverage is packaged in a can.

Figure 3 shows a mechanism which may be interposed between a filling mechanism and a sealing mechanism to partially immerse a can in a body of hot water for the purpose of the present invention. The numeral 70 designates an endless conveyor to which cans move from the filling mechanism, this conveyor terminating adjacent a tank 71 of suitably heated water. A conveyor 72 is positioned above the outlet end of conveyor 70 and extends over the tank 71. Conveyor 72 has forked hooks 73 pivoted thereto and as the conveyor 72 moves, these hooks will drop from a guide plate 74 to engage about the neck of a filled can on conveyor 70 to move the can from the latter conveyor and carry it through the water in the tank 71. As shown, the central portion of the lower run of conveyor 72 is depressed to lower the can into the tank. The conveyor 72 will place the cans upon a conveyor 75, the hooks 73 being momentarily detained at

the instant the can reaches a firm position on the latter conveyor by suitable trip means, not shown, for example, a pivoted arm lightly spring-pressed to momentarily retard advancing movement of the hook so that the can may move out of engagement therewith.

The can is preferably immersed to one-third its height in the water. Such immersion of a can of beer for a few seconds, with the water at a temperature of from 140° to 160° F., depending upon the temperature of the beverage, will cause a compact and stable foam to fill the headspace of the container. If the can is immersed to a greater depth, the water temperature may be reduced. For example, it is found that with a can one-third immersed in water at 140° F., and with the beverage at 45° F., the headspace will be filled with a stable, controllable foam in thirty seconds. With other conditions identical, immersion in water at 160° will fill the headspace in fifteen seconds.

As hereafter stated, the periods of heating just stated must be reduced with some soft drinks.

It is to be understood that the type of foam which may be created by the present invention, at least with beer, is formed of very fine bubbles and is very compact due to the relatively slow heating, thereby substantially excluding all air from the container headspace. It is also extremely stable and will remain in place for several minutes. This type of foam is also controllable; that is, the formation of the foam will discontinue immediately or almost immediately the application of heat is terminated. All of these characteristics distinguish the foaming obtained by the present invention from the foaming which may occur as the result of a general, as opposed to a localized, application of heat or the tapping or other agitation of the container and contents, for in the latter instances the foaming is sudden and violent and in extremely large bubbles which further increase in size as they move upwardly through the beverage. Also, foaming caused by these last-mentioned methods is uncontrollable and may continue indefinitely so that a large gas or liquid loss may occur and the foam may or may not remain in the headspace for a suitable period to permit sealing.

The foam which occurs with beer by the use of the present invention is formed of quite small bubbles and builds up relatively slowly. With most soft drinks, the bubbles are somewhat larger, form more rapidly, and the foam which results is not quite so stable, requiring that the bottle be capped as soon as possible after heating is discontinued, and also that the period of application of heat be reduced. Moreover, the controlled foaming which occurs with soft drinks varies with the different beverages, some foaming more rapidly than others and some, for example, ginger ale, producing a more stable foam.

The phraseology employed in the specification is for the purpose of description and is not intended to limit the invention, the scope of the invention being indicated in the claims.

I claim:

1. A method of removing air from a receptacle containing a carbonated beverage, between the filling machine and sealing machine, comprising subjecting the beverage in an open receptacle to an elevated temperature materially below the boiling point of said beverage, by rapidly heating the exterior of the receptacle while maintaining

the beverage at atmospheric pressure and at such temperature, for a sufficient period of time to cause foaming of the beverage and elimination of the air, and then as soon as the foam reaches the top of the receptacle, immediately sealing the latter and thereby preventing the loss of CO₂ from the beverage.

2. The combination in a filling machine, of a container filling mechanism, a container sealing mechanism, means to move a container from the filling mechanism to the sealing mechanism, a body of water in the path of travel of a container between said mechanisms, and means to maintain the body of water at sufficient temperature to heat the container contents sufficiently to liberate carbon dioxide therefrom and expel at least a part of the air from the space above such contents.

3. The combination in a filling machine, of a container filling mechanism, a container sealing mechanism, a body of water between said mecha-

nisms, means to engage a container leaving said filling mechanism and carry the same at least partly immersed in the water and position it adjacent the sealing mechanism, and means to maintain the body of water at sufficient temperature to heat the container contents sufficiently to liberate carbon dioxide therefrom and expel at least a part of the air from the space above such contents.

10 4. A mechanism for liberating carbon dioxide from liquid within an open container comprising a water tank, means to engage a container and move the same partly immersed in the water in said tank, and means to maintain the water within said tank at sufficient temperature to heat the container contents sufficiently to liberate carbon dioxide therefrom and expel at least a part of the air from the space above such contents.

SAMUEL HENRY AYERS.
